UNITED STATES PATENT OFFICE.

WILLIAM T. BRIGHAM, OF BALTIMORE, MARYLAND.

DESIGN FOR A HAT-BAND.

SPECIFICATION forming part of Design No. 20,255, dated November 4, 1890.

Application filed October 10, 1890. Serial No. 367,728. Term of patent 3½ years.

To all whom it may concern:

Be it known that I, WILLIAM T. BRIGHAM, a citizen of the United States, residing at Baltimore, in the State of Maryland, have invented and produced a new and original Design for Hat-Bands, of which the following is a specification.

In the drawings herewith, Figure 1 is a view of a hat with a band of my design. Fig. 2 is a view, on a larger scale, of the hat-band separated from the hat. Fig. 3 is another view of the band, showing a modification in the design.

The hat-band A has two loops or folds *b b'*, one in front of the other, or, in other words, a narrow central fold *b'* outside of a broad fold *b*. These loops or folds are in imitation of a bow. The central fold has two circular rosettes or coils *c c'*, one above the other and

connected by a strand *d*. When viewed in elevation, the circular rosettes or coils resemble two ornamental buttons. These parts constitute the ornamental design. These circular rosettes or coils may be black and white, all black, or in colors. Those shown in Fig. 2 are in spiral form simply, while those shown in Fig. 3 are also spiral with a small center disk or button *e*.

I claim—

The ornamental design for hat-bands, substantially as herein shown and described.

In testimony whereof I affix my signature in the presence of two witnesses.

WILLIAM T. BRIGHAM.

Witnesses:

A. O. BABENDREIER,
JNO. T. MADDOX.
